SHOE

Charles Miller, Long Island City, N. Y.

Application January 22, 1934, Serial No. 707,626

2 Claims. (Cl. 36—17)

My invention relates to shoes and deals more specifically with shoes having specially prepared soles designed to render the shoes more comfortable, and healthful as well as to enhance its 5 appearance.

For the purposes of this application, I shall show and discuss my invention in its adaptation to a welt shoe. It will be understood, however, that such treatment is purely illustrative and in 10 no way limiting. The construction of my shoe is described and illustrated in the accompanying specification and drawing and the characteristic features of novelty are particularly pointed out in the appended claims. Throughout the specification and drawing like reference characters 15 are correspondingly employed, and in the drawing:

Fig. 1 is an exploded view of a shoe embodying the present invention.

Fig. 2 is a plan view of the intermediate sole used in this invention.

Fig. 3 is a transverse section of a completed shoe taken across the forward portion thereof.

Referring in detail to the drawing, the shoe 25 10 having an upper 11, a welt 12, and an insole 13 is assembled on a last 14. The upper is lasted and the welt is attached in the manner well understood in connection with the manufacture of welt shoes.

An intermediate sole 20 is provided, having the tread portion thereof cut out by means of a suitable die, or otherwise to form a rand 21 integral with the shank and heel portion 22. I 35 preferably use a blank of sole leather specially treated to render the same soft and pliable. The opening defined by the rand 21 and the portion 22 may be any desired shape but I preferably shape it to be substantially coextensive with the tread surface of the outsole, leaving the rand 21 40 which is of a width of about one half inch to one inch.

I now prepare a sheet 25 of latex or other suitable composition of the exact size and thickness to fit into the opening defined by the rand. The 45 sheet 25 closes the opening and thus provides an intermediate sole having a rubber or composition section. An outsole 30 together with the intermediate sole 20 are sewed to the welt 12, by stitching 40 thus positioning 20 in its intermediate position, and enclosing the sheet of rubber 25 between the outsole 30 and the insole 13.

It is an important consideration in preparing the insole, upper, and welt structure that the 50 edge 12a of the welt 12, which is sewed to the upper and lip of the insole be trimmed close to

the bottom surface of the insole so that the welt finally lies in substantially the plane of the bottom surface of the insole, and the seam which joins welt, upper, and insole lip lies substantially flush with the bottom surface of the insole. 5

By virtue of this feature the filling commonly used in welt shoes is dispensed with, and in my structure the bottom surface of the welt and the insole contact in intimate relation with the intermediate sole. 10

At the tip of the toe portion however, in certain cases, I find it advisable to use a slight filling, due to the gathering at this point of the upper, lining and welt, and the consequent difficulty in getting the flush relationship described 15 above. For this purpose I preferably use a piece of sole leather 15 trimmed to the desired dimensions. It will be understood, of course, that this feature is not always necessary, for, depending on the character of materials used, I may obtain 20 a sufficiently flat structure at this point to preclude the use of this filler.

Following the attachment of the outsole it is merely necessary to trim the edges, attach the heel, and perform the other usual finishing operations. 25

Any suitable filler may be used in place of the sheet 25, such as ground cork, felt, or rubber compositions.

Having thus described my invention, I claim: 30

1. In a welt shoe, an insole having a lip, an upper, a welt, said upper and welt being sewed to said lip, said welt when in the assembled shoe lying substantially in the plane of the bottom surface of the insole, an intermediate sole provided with a rubber section of a thickness substantially equal to that of the intermediate sole, and an outsole joined to said welt and said intermediate sole, the rubber section being normally 35 in contact with the bottom surface of the 40 insole and with the top surface of the outsole.

2. In a welt shoe, an insole having a lip, an upper, a welt, said upper and welt being sewed to said lip, said welt when in the assembled shoe lying substantially in the plane of the bottom 45 surface of the insole, an intermediate sole comprising a rand section outlining an opening, and a section shaped to fill said opening and of a thickness substantially equal to the thickness of said intermediate sole disposed within said 50 opening, and an outsole joined to said welt and intermediate sole, said section being normally in contact with the bottom surface of the insole and with the top surface of the outsole.

CHARLES MILLER. 55
